(57) **CLAIM**

We claim the ornamental design for a spring type reverberator, as shown and described.

DESCRIPTION

FIG. 1 is a perspective view of our new design;
FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Elements in the Figures shown as broken lines are unclaimed portions of the design.
